TALL OIL TREATMENT

Ernest Segesemann, Newark, N. J., assignor to
 National Oil Products Company, Harrison,
 N. J., a corporation of New Jersey

No Drawing. Application December 16, 1939,
 Serial No. 309,703

7 Claims. (Cl. 260—97.5)

This invention relates in general to the production of valuable products from tall oil, and more particularly to a process of separating tall oil into its main constituents, i. e., fatty and resinic acids.

"Tall oil" or "talloel," which literally means "pine oil," is the resinous and fatty by-product obtained chiefly in the production of paper pulp from resin-bearing woods by the so-called sulphate process. In the sulphate process wood is 10 digested with an alkaline liquor containing sodium sulphate, during which process tall oil accumulates in the form of its sodium soap on the surface of the waste liquor. The main constituents of this oil, after acidification, comprise resinic acids and fatty acids, the latter consisting mainly of oleic, linoleic and linolenic acids, each of which are valuable commodities in substantially pure form. Various processes have been proposed in an attempt to effect separation of tall oil into its main constituents, i. e., fatty acids and resinic acids. One process comprises esterifying the fatty acids in tall oil with a low boiling alcohol and separating the resulting fatty ester from the free rosin acids by distillation or by alkali extraction. Another known process comprises esterifying the fatty acids with a polyhydric alcohol and distilling off the resinic acids. According to another process, both the fatty acids and the resinic acids are esterified with a polyhydric alcohol and the resin esters are then catalytically split and the liberated resinic acids distilled off. While the foregoing and other known processes have been employed with varying degrees of success, they all exhibit certain disadvantages, primarily in that only partial separation is effected. Moreover, the fatty acid fraction obtained by these processes, consisting mainly of a mixture of oleic, linoleic and linolenic acids, is not particularly suitable for a wide variety of industrial uses. Usually having an iodine value of about 120 or 130, this fatty acid fraction (or its esters) shows some drying properties, but these drying properties are not pronounced enough for a drying oil of good quality. On the other hand, this fatty acid fraction is too highly unsaturated to find extensive application in some of the largest fat-consuming industries, namely the soap industry, and in the manufacture of specialties for the textile and tanning trades, the bulk of fats used in these industries being of the more highly saturated type.

The general object of this invention is to obviate the foregoing and other disadvantages.

A specific object of the invention is to provide

an improved and more efficient process for separating tall oil into its main constituents.

A further object of the invention is to provide an improved process for separating tall oil into its constituents and recovering the fatty acids in a more saturated form so that the same can be adapted to a wider industrial use.

Other objects will in part be obvious and will in part appear hereafter.

The foregoing and other objects are accomplished according to the broader aspects of the invention whereby tall oil in its acid and/or ester form is dissolved in a suitable solvent and subjected to temperatures sufficiently low to effect precipitation of a certain fraction of or all of the fatty acids or esters thereof, followed by removal of said precipitated fraction by filtration or centrifuging or by any other known means of separating an insoluble solid from a liquid.

For the purposes of this invention, the tall oil esters of the monohydric aliphatic alcohols containing from 1 to 5 carbon atoms are considered equivalent to the tall oil acids, and are, therefore, to be included in the generic expression "tall oil."

The resinic acids alone or in admixture with the more highly unsaturated fatty acids remaining in the solvent may be recovered by distilling off the solvent. The tall oil or its esters employed in accordance with the process of the invention may be in the crude or distilled state and they may be subjected to partial or complete hydrogenation before being subjected to the chilling and separating steps. If the tall oil used in the above mentioned process is of the crude or distilled type and has not been subjected to hydrogenation, the filtrate obtained upon separation of the precipitated fatty acids will also contain fatty acids or esters of the more highly unsaturated type, mostly linoleic and linolenic acids.

These higher unsaturated fatty acids may then be separated from the rosin by esterification followed by alkali extraction of the rosin, or by methods disclosed in my co-pending applications, Serial Nos. 217,974 and 303,535, filed July 7, 1938, and November 9, 1939, respectively. If the tall oil or its esters are hydrogenated to a degree where at least all the highly unsaturated fatty acids have been converted to oleic acid, the fatty acid fraction can be completely separated from the resinic acids by cooling and filtration alone.

This invention accordingly comprises the several steps and the relation of one or more of such steps with respect to each of the others thereof, which will be exemplified in the process

hereinafter disclosed, and the scope of the invention will be indicated in the claims.

In carrying out the process of the invention, the first step involves the dissolving of tall oil in a suitable solvent therefor which is characterized by the property of retaining the resinic acids or derivatives thereof in solution at low temperatures and permitting the fatty acids or derivatives thereof to precipitate out at low temperatures. Examples of such solvents include, inter alia, petroleum hydrocarbons, such as, gasoline, kerosene, heptane, mineral spirits, etc.; aromatic hydrocarbons, such as, benzene, toluene, xylene, etc.; alcohols, such as ethyl alcohol, methyl alcohol, isopropyl alcohol, etc.; ketones, such as acetone, ethyl methyl ketone, cyclohexanone, etc.; chlorinated hydrocarbons, such as, ethylene dichloride, trichlorethylene, etc. The tall oil may be in a crude or a partially or completely refined state at the outset; moreover, the tall oil may be in its usual acid form and composed essentially of a mixture of rosin and fatty acids. The tall oil may also be used in its partially or completely esterified form, i. e., the fatty acids in the tall oil may be esterified with a monohydric aliphatic alcohol, preferably containing not more than 5 carbon atoms, whereby the rosin acids remain in their acidic form, or both the fatty and rosin acids may be in their esterified form.

The tall oil in any of its aforementioned forms may be subjected to varying degrees of hydrogenation before the chilling step, depending upon the type of end products desired. For example, the fatty acids found in tall oil comprises essentially oleic, linoleic and linolenic acids, the latter two of which are highly unsaturated as compared to oleic acid, which contains only one double bond. The solubility of the highly unsaturated acids such as linoleic and linolenic acids and their esters is somewhat comparable to the rosin acids and they remain in solution along with the rosin acids during the chilling operation during which the oleic acid or its esters precipitate out. Such a result in certain cases is desirable, i. e., to remove the oleic acid and recover the mixture remaining in the solvent, which comprises essentially rosin acids and linoleic and linolenic acids or their esters. From this latter mixture the unsaturated fatty acids may be separated from the rosin acids by any suitable process including those aforementioned. Moreover, this mixture of rosin acids and unsaturated fatty acids may be used as such in the preparation of other products such as drying oils, which is to form the subject matter of another application.

Where it is desired to substantially completely recover the fatty acids in a more saturated form from the rosin acids, the original tall oil fatty acids or esters are subjected to partial or complete hydrogenation, depending on the type of fatty acids desired. For example, partial hydrogenation of the fatty acids may be carried on to convert the linoleic and linolenic acids to oleic acid, whereby oleic will constitute substantially all of the fatty acids. On the other hand hydrogenation may be carried on further to decrease the degree of unsaturation in the resulting fatty acids, whereby all or substantially all the fatty acids will be converted into stearic acid or a mixture having an average iodine value of about 10 or less. The tall oil in any of its aforementioned forms may be subjected to hydrogenation either before or after it has been dissolved in the desired solvent; moreover the hydrogenation may be effected before esterification in those

cases where the tall oil acids are partially or completely esterified before the chilling operation. The hydrogenating operation may be carried out according to known procedures by the use of hydrogen and a catalyst and under the influence of heat and pressure.

After the desired tall oil composition has been dissolved in a suitable solvent, the temperature of the solution is decreased to obtain the desired degree of precipitation of fatty acids or esters thereof. By actual experiment, precipitation of the fatty materials is effected within a temperature range of about 5° C. to -70° C. It is obvious, of course, that temperatures outside of this range may also be operative to carry out the objects of the invention. The degree of cooling will be varied according to the nature of the solvent used and according to the form in which the fatty and resinous materials occur. Moreover, the degree of hydrogenation of the tall oil constituents will play an important role in determining the time and temperature under which precipitation will be effected. The precipitated fatty acids or esters are removed from the solvent solution by any suitable means including centrifuging and filtration. The precipitated products after removal are preferably washed with a suitable solvent, i. e., the same solvent as used in the process, and preferably at substantially the same temperature at which the precipitating operation was carried out.

For a fuller understanding of the nature and objects of the invention, reference should be had to the following examples, which are given merely to illustrate the invention and are not to be construed in a limiting sense.

Example I

100 gms. of distilled tall oil (having a rosin content of 32%) were dissolved in 650 ml. of acetone and cooled to -60° C. for 1 hour. The oleic acid fraction which has crystallized out is then washed with 350 ml. of fresh acetone which has previously been cooled to -60° C. 40 gms. of fatty acids were obtained which consisted chiefly of oleic acid having an iodine value of about 80 and being practically free from rosin.

From the filtrate the solvent was distilled off and the residue consisting mainly of rosin, linoleic and linolenic acids was esterified by heating 50 gms. of it with 5.5 gms. of anhydrous glycerol at such a rate that the temperature gradually rose and reached 280° C. at the end of the sixth hour. The product thus obtained has excellent film-forming properties and may be used in the manufacture of varnishes as a substitute for linseed oil and ester gum.

Example II

100 gms. of distilled tall oil were dissolved in 700 ml. of ethyl alcohol. The solution was maintained at -60° C. for two hours, and the crystallized fatty acids were filtered and washed with fresh alcohol which had previously been cooled to -60° C. The filter cake was freed from any residual alcohol by vacuum distillation. 42 gms. of rosin-free fatty acids were obtained having an iodine value of 71.5 and an unsaponifiable content of 1.8%.

To the above filtrate there was added 0.35 gm. of sulphuric acid and the mixture was refluxed for four hours. The sulphuric acid was then neutralized with an equivalent quantity of caustic soda and the excess alcohol was recovered by vacuum distillation. The residue was then

dissolved in 200 ml. of commercial heptane and caustic soda of 12% strength was added with rapid stirring in an amount 10% in excess of that needed to neutralize the rosin acids. The rosin soap which settled to the bottom of the vessel was then drawn off and was washed once with 100 ml. of heptane. The solution of the ethyl esters in heptane was then washed with water until the last traces of soap had been removed and finally the heptane was distilled off to recover the ethyl esters of the highly unsaturated fatty acids.

The rosin soap was then dissolved in water and split with sulphuric acid to recover the rosin in a free state.

Example III

Distilled tall oil was hydrogenated under a pressure of 10 atmospheres and at a temperature of 120° C. for one-half hour using 2% of nickel as a catalyst. Analysis of the product showed that practically all of the highly unsaturated acids had been selectively and partially hydrogenated to oleic acid, while the oleic acid and the rosin originally present had either not or only very slightly reacted with the hydrogen. The fatty acids separated by analytical means, i. e., by the esterification and alkali wash method had an iodine value of 89.7, comparing favorably with that of oleic acid of commercial quality. 100 gms. of the partly hydrogenated product were dissolved in 800 ml. of acetone and cooled to -60° for 2 hours. The oleic acid which had crystallized out was filtered off and washed with 400 ml. of fresh cold acetone. 63 gms. of oleic acid were obtained.

The rosin was recovered from the filtrate by distilling off the acetone.

Example IV

Distilled tall oil (having a rosin content of 32%) was hydrogenated for two hours at a pressure of 120 atmospheres and at temperatures ranging from 150° C. to 200° C. using 2% nickel as a catalyst. 100 gms. of the hydrogenated product which had an iodine value of 28.1 and a titer of 52.4° C. was dissolved in 1000 ml. of methanol. The solution was cooled at -6° C. for 8 hours and the precipitated fatty acids were then filtered off and washed three times with 100 ml. portions each of methanol which had previously been cooled to -6° C. The fatty acids thus obtained were substantially free from rosin and consist of a pure white solid having a melting point of 57° C.

The filtrate upon distillation of the solvent yielded a heavy viscous fluid of light-brown color consisting chiefly of the rosin, some unsaponifiable matter and a small portion of fatty acids.

Example V

The fatty acids in 100 gms. of distilled tall oil were esterified by refluxing for three hours with 50 ml. of methanol and 2 gms. of sulphuric acid. The product (after distilling off the excess alcohol and washing out the sulphuric acid) was composed of 70% methyl esters of the fatty acids, 6% of unsaponifiable matter and 24% of free rosin. This mixture was then hydrogenated for 2 hours at a pressure of 140 atmospheres and at a temperature of 170° C. in presence of 3% of nickel as a catalyst.

100 gms. of the hydrogenated product which had an iodine value of 25.4 were dissolved in 750 ml. of acetone and cooled at -18° C. overnight. The precipitated esters of the fatty acids were

then filtered off and washed four times each, with portions of 70 ml. acetone cooled to -18° C. The filter cake consisting of the methyl esters of the fatty acids is a pure white solid below room temperature and upon analysis it showed a rosin content of .32% and an iodine value of 9.7.

The rosin was then recovered from the filtrate by distilling off the acetone.

Example VI

100 gms. of the methyl esters of tall oil, which were prepared by completely esterifying tall oil under pressure with methanol, were hydrogenated to an iodine value of 18.5. The hydrogenated product was then dissolved in 600 ml. of ethylene chloride and cooled at -18° C. for 12 hours. The solid methyl esters of the fatty acids were then filtered off and washed several times with cold ethylene chloride. The methyl esters thus recovered had a rosin content of 1.9%.

15 The methyl abietate in the filtrate was then recovered by distilling off the solvent.

Example VII

25 In a closed vessel which was provided with a reflux condenser, 100 gms. of distilled tall oil having a rosin content of 35% were heated with 11 gms. of anhydrous glycerol at such a rate that the temperature rose gradually to 280° C. during six hours. The triglyceride of tall oil thus obtained (having an acid value of 3.0) was then hydrogenated at a pressure of 7 atmospheres and at a temperature of 150° to 160° C. using 2% of nickel as a catalyst. The hydrogenated product had an iodine value of 46.0.

30 100 gms. of the hydrogenated product were dissolved in 700 ml. of gasoline and cooled to -5° C. for 6 hours. The solid fraction was removed by filtration and washed with fresh gasoline. The product thus obtained was a white solid containing 18.5% of combined rosin.

35 Upon distillation of the gasoline from the filtrate, a heavy viscous fluid was obtained consisting of mixed triglycerides high in combined rosin content.

40 45 While the present invention is particularly adapted for the treatment of tall oil, it is within the purview of the invention to employ the process for separating resinic acids from fatty acids present in any mixture.

50 55 Since certain changes may be made in carrying out the above process without departing from the scope of the invention, it is intended that all matter contained in the above description shall be interpreted as illustrative and not in a limiting sense.

60 65 It is also to be understood that the following claims are intended to cover all the generic and specific features of the invention herein described, and all statements of the scope of the invention, which as a matter of language might be said to fall therebetween.

Having described my invention, what I claim as new and desire to secure by Letters Patent is:

65 70 1. A process of treating hydrogenated tall oil to separate fatty acids therefrom which comprises dissolving tall oil which has been hydrogenated to the extent wherein the original unsaturated fatty acids, more unsaturated than oleic acid, have been converted at least to oleic acid in a suitable solvent therefor, decreasing the temperature thereof to effect precipitation of fatty acids and removing the precipitated fatty acids from the remaining solution.

75 2. A process of treating tall oil to separate

oleic acid therefrom which comprises converting the linoleic and linolenic acids in tall oil to oleic acid by hydrogenation, dissolving the hydrogenated oil in a suitable solvent therefor, decreasing the temperature to effect precipitation of oleic acid and removing the precipitated acid from the remaining solution.

3. A process for treating tall oil to separate fatty acids therefrom which comprises hydrogenating tall oil to convert the unsaturated fatty acids into saturated fatty acids, decreasing the temperature of the resulting hydrogenated oil in the presence of a solvent therefor to effect precipitation of the fatty acids and removing the precipitated fatty acids from the remaining solution.

4. A process for treating tall oil to separate the fatty acids therefrom which comprises dissolving the tall oil in a suitable solvent therefor, hydrogenating the fatty acids in the tall oil solution to the extent wherein the original unsaturated fatty acids, more unsaturated than oleic acid, have been converted at least to oleic acid, decreasing the temperature of the solution to effect precipitation of fatty acids and removing the precipitated fatty acids from the remaining solution.

5. A process of treating tall oil to separate

fatty acids therefrom which comprises hydrogenating the fatty acids of tall oil under the influence of heat and pressure to the extent wherein the original unsaturated fatty acids, more unsaturated than oleic acid, have been converted at least to oleic acid, dissolving the hydrogenated product in acetone, decreasing the temperature of the solution to effect precipitation of the fatty acids and removing the fatty acids from the rosin-acetone solution.

6. A process of treating tall oil to separate the fatty acids therefrom which comprises converting the fatty acids in tall oil to their substantially completely saturated form by hydrogenation, dissolving the resulting mass in methanol, cooling the solution to a point below 0° C. to effect precipitation of the fatty acids and removing the precipitated fatty acids from the remaining methanol-rosin solution.

7. In a process of separating fatty acids from tall oil which has been hydrogenated to the extent wherein the original unsaturated fatty acids, more unsaturated than oleic acid, have been converted at least to oleic acid, the step which comprises chilling a solution of such hydrogenated tall oil in an organic solvent therefor to effect precipitation of fatty acids.

ERNEST SEGESSEMAN.
